UNITED STATES PATENT OFFICE.

CHARLES A. MOORE, OF EDINA, MINNESOTA.

SYSTEM FOR CONDITIONING AIR IN STORAGE CHAMBERS.

Application filed May 1, 1926. Serial No. 106,144.

My invention relates to improvements in systems for conditioning air in storage chambers.

An object of the invention is to provide simple and effective means for electively refrigerating or heating storage chambers in produce buildings, ships and similar structures and, under either operation, to ventilate such chambers.

Another object of the invention is to provide means, as above, designed to be arranged in a chambered structure to occupy minimum storage space in the chambers and offering the minimum of interference to the handling of lading in said chambers.

With the foregoing and other objects in view, which will appear in the following description, the invention resides in the novel combination and arrangement of parts and in the details of construction hereinafter described and claimed.

In the drawings, Fig. 1 is a vertical longitudinal sectional view of a building with my improved system applied thereto, said view being taken as on the line 1—1 of Fig. 2; Fig. 2 is a transverse sectional view of the structure shown in Fig. 1, said view being taken as on the line 2—2 of said Fig. 1 and Fig. 3 is a detail plan view of the housing surrounding the structure, the roof of said housing being removed to disclose the various parts therein.

Referring to the accompanying drawings, it will be observed that the building illustrated includes the usual sidewalls 10 and 11, endwalls 12 and 13, floors 14 and roof 15 providing chambers A within said building. Crossing the floor 14 of each chamber A are sleepers 16 upon which floor slats 17 are fastened, said floor slats forming a false perforate floor providing an air passage B therebeneath. Against the sidewall 10 are upright timbers 18 to which wall slats 19 are secured. These wall slats form a false perforate sidewall between which and the adjacent sidewall 10 of the building is an air passageway C, said passageway being in communication with the floor passageway B. Adjacent to the opposite sidewall 11 of the building, in each chamber A, is a solid false sidewall 20 resting at its lower edge on the upper edges of the sleepers 16. Midway between floor and ceiling is a horizontal partition strip 21 dividing the space between the solid false wall 20 and the sidewall 11 of the building into upper and lower conduits D and E, the

lower conduit E being open at the bottom thereof to the air passageway B beneath the floor slats 17. The upper edge of the solid false wall 20 stops short of the ceiling leaving a port F through which communication is afforded between the upper portion of the chamber A and the upper portion of the conduit D. Fitted to the port F in each of the chambers is a frictionally hinged gate 22, which may be adjusted to regulate the openings afforded by said ports F. An upright space is left between the endwall 12 of the building and the adjacent ends of the solid false sidewalls 20 in the various chambers A, said space extending through the floors 14.

In this space is placed an air main 23, the same reaching from the lower conduit E in the lowermost chamber A through the roof 15 and thence along the roof into the lower portion of a housing 24 located upon the roof. Said main 23 opens into each lower conduit E in each chamber A, as shown at 25. An upright space is also left between the endwall 13 of the building and the adjacent ends of the solid false walls 20 in the chambers A, said space also extending through the floors 14. In this latter noted space is placed an air main 26 which reaches from the upper conduit D in the lowermost chamber A through the roof 15, thence into the upper portion of the housing 24 at the end thereof opposite the end through which said first main 23 enters said housing. The upper conduits D communicate with the main 26 through openings 26a in said main. Travelling this housing 24 between said ends thereof is an upright partition 27 dividing the housing into a compartment G and a room H, said compartment and room being brought into communication one with the other by means of an elevated horizontal pipe 28 passing through said partition 27. In front of the open end of this pipe 28 in the room H is a fan 29, the same being driven in reverse directions by means of an electric motor 30 mounted upon the outside of the housing 24 and connected with the fan 29 through a drive shaft 31, reaching through one end of said pipe 28.

Also within the room H is an upright pipe 32, which stops short of the ceiling of the room at its upper end and short of the floor of the room at its lower end. A horizontal pipe 33 branching off from said upright pipe 32 medially thereof extends through the side of the housing 24 bringing said latter pipe 32 into communication with

the outer air. Near the top of this pipe 32 is a damper 34, a similar damper 35 being provided in said pipe near the bottom thereof. Within the compartment G of the housing 5 and duplicating the above mentioned upright pipe 32, branch pipe 33 and dampers 34 and 35 are an upright pipe 36, branch pipe 37 and dampers 38 and 39. Also within the compartment G are a number of staggered tiers 10 of coils 40 for conveying any suitable temperature affecting medium through said compartment.

In use, lading is freely trucked over the slatted false floors of the chambers A without interference with or from the parts of the system associated with said chambers. Such lading to be stored in the chambers A are stacked in tiers spaced apart from each other and from the wall slats 19 and also spaced at 20 the tops of the stacks from the ceilings of the chambers.

In the use of the system under refrigeration, a refrigerating medium is circulated through the coils 40 in the compartment G of the housing 24 and the fan 29 propelled in a direction to force air into the horizontal pipe 28 from the fan room H. Thus acting said fan draws air through the main 26, upper conduits D and ports F from across the ceilings of the chambers A and forces said air through the coil compartment G where it is cooled by contact with the cold coils 40, thence down the main 23 and thence through the lower conduits E into the air passageways B beneath the floor slats 17. From these passageways B a part of the cold air filters upwardly through said floor slats and stacked lading under the force of the fan 29 and the natural tendency to rise about the 35 relatively warm lading, which ascending air continues upward to the ceilings of the chamber A to replace the warmest air being drawn therefrom by the fan 29, as above explained. The remainder of the cold air reaching the 40 wall passageways C through the floor passageways B ascends through said former passageways by force of the fan 29 augmented by the natural tendency of said air to rise along the relatively warm sidewall 10. This 45 ascending air filters between the wall slats 19 into the chambers A, finally, in part, reaching the upper corners of the chambers opposite the ports F from whence it is drawn into said ports by the fan 29. Thus it will 50 be understood that a convective and diffused circulation of refrigerated air is set up within the chambers A.

Under heating, a heating medium is conveyed through the coils 40 and the fan 29 reversed to draw air through the horizontal pipe 28, the movement of air through the mains 23 and 26, conduits D and E, and passageways B and C being the reverse of the movement of air under refrigeration, as 55 above explained, a convective and diffused

circulation of warm air being set up in the chambers under the action of the fan augmented in part of the circuit by the action of gravity.

Under refrigeration or under heating, 70 fresh air may be admitted to the circulating air to replace air that is permitted to be expelled from the system. This is accomplished by opening one or the other or both of the dampers in both of the upright pipes 32 and 36, air being expelled from the system out of the pipe on the pressure side of the fan 29 and fresh air drawn into the system through the other of the two pipes on the suction side of said fan. Election is made between the 80 upper and lower dampers in the pipes 32 and 36 according to the existing atmospheric conditions, whereby the percentage of humidity in the air within the system may be increased or diminished. For example, under 85 refrigeration, and to increase the percentage of humidity in the air within the system, I close the upper damper 34 in pipe 32 and open the lower damper 35 therein. I also close the upper damper 38 in pipe 36 and open the lower damper 39 in said pipe. With this adjustment of dampers, warm air from without is drawn into the fan room H under the incoming stream of colder air from the main 26, the result being that the percentage of 90 humidity of the air within the room H is increased. Further, the opening of the lower damper 39 in pipe 36 permits of the forcing from the coil compartment G of the driest air at the lower portion thereof.

Changes in the specific form of my invention, as herein disclosed, may be made within the scope of what is claimed without departing from the spirit of my invention.

Having described my invention, what I 105 claim as new and desire to protect by Letters Patent is:

1. The combination with a structure providing a storage chamber, of a false perforate floor in said chamber providing an air passageway between the same and the main floor of the chamber, a false perforate sidewall at one side of the chamber providing an air passageway between the same and the adjacent main sidewall, said passageways communicating one with the other, a solid false sidewall at the other side of the chamber providing a space between the same and the adjacent sidewall of said chamber, said solid false sidewall terminating short of the ceiling of the chamber to provide a port between said space and said ceiling, a horizontal partition in said space dividing the same into upper and lower conduits, the former communicating along its upper portion, through said port, with the upper portion of the chamber and the latter communicating along its lower portion with the air passageway at the floor of the chamber, an adjustable gate for said port, a housing surmounting the 110 115 120 125 130

structure, an upright partition in the housing dividing the same into a compartment and a room, coils in said compartment for a temperature affecting medium, said upright partition having an opening therethrough bringing the coil compartment and said room into communication one with the other, a fan in said room associated with said opening, an air main providing communication between the lower conduit and the coil compartment, a second main providing communication between the upper conduit and the fan room, means for bringing the interior of the fan room into communication with the outer air, and means for bringing the interior of the coil compartment into communication with the outer air.

2. The combination with a structure providing a storage chamber, of a false perforate floor in said chamber providing an air passageway between the same and the main floor of the chamber, a false perforate sidewall at one side of the chamber providing an air passageway between the same and the adjacent main sidewall, said passageways communicating one with the other, upper and lower conduits extending along the other sidewall, the former having communication at the upper portion thereof with the upper portion of the chamber and the latter having communication at its lower portion with the air passageway beneath the false floor, one conduit providing for the ingress of air to the chamber and the other conduit providing for the egress of air from said chamber, a fan for setting up a flow of air through said conduits and circulating the same in said chamber, and means for affecting the temperature of the air in its passage to the chamber.

3. The combination with a structure providing a storage chamber, of a false perforate floor in said chamber providing an air passageway between the same and the main floor of the chamber, upper and lower conduits extending along a sidewall of the chamber, the former having communication at the upper portion thereof with the upper portion of the chamber and the latter having communication at its lower portion with the air passageway beneath the false floor, one conduit providing for the ingress of air to the chamber and the other conduit providing for the egress of air from said chamber, a fan for setting up a flow of air through said conduits and circulating the same in said chamber, and means for affecting the temperature of the air in its passage to the chamber.

4. The combination with a storage chamber of upper and lower conduits extending along a sidewall thereof, the former having communication at the upper portion thereof with the upper portion of the chamber and the latter having communication at its lower portion with the lower portion of the chamber, one conduit providing for the ingress of air to the chamber and the other conduit providing for the egress of air from said chamber, a fan for setting up a flow of air through said conduits and circulating the same in said chamber, means for affecting the temperature of the air in its flow to the chamber, and means for freshening the air in such passage adapted to admit outer air to the flow on the suction side of the fan and permit of the escape of air from such flow on the pressure side of the fan.

In testimony whereof, I have signed my name to this specification.

CHARLES A. MOORE.
